UNITED STATES PATENT OFFICE.

ALFRED ERNEST HUDD, OF NEW BRIGHTON, AND ARTHUR FRANK BOUND, OF
TIMPERLEY, ENGLAND.

TIME-ELEMENT DEVICE.

Original application filed October 29, 1921, Serial No. 511,322. Divided and this application filed
September 25, 1922. Serial No. 590,360.

To all whom it may concern:

Be it known that we, ALFRED ERNEST HUDD and ARTHUR FRANK BOUND, subjects of the King of Great Britain and Ireland, and residents, respectively, of New Brighton, Cheshire, England, and Timperley, Cheshire, England, have invented certain new and useful Improvements in Time-Element Devices, of which the following is a specification.

The present invention relates to an improved time element device for use in train control systems; such a time element device consists essentially of a member controlled in such a manner that it cannot complete its movement until a predetermined time has elapsed, such time element device being used for controlling the application of the brakes if the train passes between two points in less than the time for which the time element device is set, and the object of the invention is to provide a time element device electrically operated which requires only a small amount of operating current and yet remains highly accurate.

One of the features of the present invention is an arrangement for controlling the time element device by an oscillating member, such as a balance wheel of a clock, thus rendering the device highly accurate. It is therefore of importance that the construction of the time element device could be such that it will require very little operating power and for this purpose a very special design of the coupling has been evolved by which the work to be performed by the oscillating member is reduced to a minimum. This feature of the invention consists of an arrangement for delaying the complete movement of an operating member by interposing a ball or roller loosely supported between suitably shaped surfaces of a regularly moving member and the operating member. The operating member on being subjected to a tractive force presses the ball or roller so that the regularly moving member causes it to roll between the said surfaces for a predetermined distance when a depression in the surface of the operating member will permit the operating member to complete its movement. Conveniently this feature of the invention is carried into effect by arranging that the oscillating member causes,

through a pawl and ratchet device, the step by step movement of a cylindrical disc while the armature of an electromagnet is provided with a curved arm having substantially the same centre of curvature as the disc so that when the armature is attracted it presses a roller against the surface of the disc, the roller then rolls along the operating member until it reaches a depression in the surface of the arm of the armature when the armature is freed to complete its movement and operate contact springs or the like. It will thus be appreciated that by this construction the work to be done by the oscillating member is only that of advancing the roller, on the other hand the actual power required to operate the contact springs is obtained from the electromagnet. The invention will be better understood by referring to the accompanying drawings, of which Figure 1 is identical with that shown in our copending application Serial No. 511,322, from which the present application has been divided. This figure is retained in the present application to illustrate the application of the invention to a train control system.

Figure 2 shows a sectional elevation of the improved time control element.

Figure 3 shows a side section with mechanism and coils removed.

Figure 4 shows an inverted plan with the base removed.

Figure 5 shows a side sectional elevation, and

Figure 6 shows an enlarged view of the coupling arrangement.

Figure 7 shows a plan and elevation of the contact arrangement for maintaining the movement of the vibratory member.

The construction of the time control device illustrated in Figures 2-6 will first be explained.

The time control element consists of an electromagnet 120 controlling an armature 121. This armature 121 is pivoted at 124 and is provided with an arm 123 having a curved surface 125 on one side and a projecting member 126 on the other side which normally engages with a projection 127 on the shaft 128 carrying the balance weight 129.

A shaft 130 pivoted in brackets 131 and 132 carries a ratchet wheel 133 and a cylindrical disc 134, while a bracket 135 loosely

supporting a roller 136 in close proximity to the surface of the disc 134 is loosely supported on the shaft 130. Normally the roller 136 under gravity control rests in the position shown, although this position may be adjusted by the screw 137 to the right of that shown. When the electromagnet 120 is excited, the armature 121 with its arm 123 moves a short distance sufficient to permit the projections 126 and 127 to disengage so that the balance weight 129 can commence to swing. At the same time the arm 123 moves the roller 136 into engagement with the surface of the disc 134. This movement is sufficient to break the connection between the contacts 138 and 139 (Figure 3) with the resting contacts 140 and 141 respectively, but not sufficient to permit the contacts 142 and 143 to make connection with their working contacts 144 and 145 respectively. On the release of the balance weight 129, it and its shaft 128 swing to and fro. As in a well known clock work movement a contact is closed for the electromagnet 146 in circuit with a primary cell through the balance spring 147, shaft 128, contact 148 (Figures 1, 4 and 5) and contact 149 supported by a leaf spring and arranged so that the shaft only makes electrical connection when moving in one direction. In order to attain this result, the contact 148, which projects from a drum secured to the shaft 128, has its upper half insulated and its lower half of conducting material, preferably platinum, while the contact 149 is supported on a leaf spring from a terminal and projects at right angles thereto into the path of the contact 148 as will be seen from Figure 7. The contact 149 is shaped as shown with a section similar to that of an oblique parallelogram, so that when the pin 148 is moving to the right, the upper or insulated side of the pin engages with the contact 149, but when the pin is moving to the left, the under or conducting side of the pin makes engagement. This engagement is made just before the armature on the oscillating member 12 comes under the pole pieces of the electromagnet 126. Hence it will be appreciated that the electromagnet 146 serves to attract the soft iron pole piece 147 carried by the balance weight 129 as this approaches its core so maintaining the balance weight 129 in movement. On the shaft 128 is a cam 150 adapted to engage with a roller 151 supported on a bracket 172. The bracket 172 is pivoted at 173 and carries at its upper end a pawl 170 so that the cam 150 by acting on the roller 151 causes the pawl 170 to advance the ratchet wheel 133 and with it the disc 134 one step for every complete swing of the balance weight 129. The movement of the disc 134 is imparted to the roller 136 which advances step by step between the surface of the cylindrical disc 134 and the inner sur-

face 125 of the arm 123 which is so shaped as to exert substantially uniform pressure on the roller 136 during its movement.

After a predetermined time the roller 136 advances to a position opposite recess 152 when the arm 123 can move freely and permit the armature 121 to complete its movement and cause the contacts 142 and 143 to engage with the working contacts 144 and 145 (Figure 3). On the electromagnet 120 de-energizing due to the opening of contact 119 (Fig. 1) when relay R de-energizes due to a train passing beyond insulation 118 the arm 123 falls back to its normal position releases the roller 136 which immediately restores to normal by gravity and permits the projecting member 126 to engage with the projection 127 when the balance weight 129 reaches the position shown in Figure 2 of the drawings.

It will be noted that the projection 127 is cam shaped in order to prevent any damping of the movement of the balance weight 129 so that it is assured that the member 129 will by its inertia, reach the position in which it is to be locked ready for a re-operation.

In Figure 1 it will be noted that an arm 122 is shown engaging at its extreme end with the member 129 at its outer edge, and while this serves for diagrammatic purposes, such a construction is not desirable nor is it found to be so satisfactory in practice as that shown in Figure 2. It might be mentioned that all the working parts shown in Figures 2, 3, 4 and 5 are supported by means of brackets 177 and 178 from the cover 153 of a box 154 having glass faces 155 by which the operation of the parts may be observed for inspection purposes. The cover 153 is provided with a number of terminals by means of which connection may be made both to the contacts and to the electromagnets 146 and 120. In order to render the construction weather-proof a rubber or like gasket 156 is provided between the lid 153 and the sides 156. The brackets 177 and 178 carry ball bearings 175 and 176 respectively, on which the shaft 128 can oscillate with negligible damping.

The operation of the train control system will now be described by reference to Figure 1 in which D₁ represents the distant signal, H represents the home signal adjacent a length of track over which it will be assumed that it is desirable to control the speed of the train. At the home signal H starting signal S and advance starting signal Y train stops TS are fitted, while at a point somewhat in advance of these train stops is an auxiliary train stop ATS. The train stops may be of any well known construction except that the train stop ATS must be electromagnetically controlled. The train stops TS may be either electromagnet-

ically controlled or mechanically controlled and are adapted to be brought to "off" position only when the corresponding signal shows "clear." As an example of how these train stops may be made and how they operate reference is made to British Patent No. 6807/14.

The auxiliary train stop is located at a position which is determined by the local 10 conditions. It is assumed that a certain block clearance is allowable beyond the home signal H in which a train must pull up as to pass beyond this limit when the signal is at "danger" is to run the danger 15 of an accident. Consequently, if the train is travelling below a certain speed the train stop TS at the home signal H would be able to bring it to rest within the block clearance, but if the train is exceeding a 20 certain speed then the auxiliary train stop ATS must come into action and the position is so chosen that if a train is going at its maximum possible speed it will always be pulled up within the block clearance past the home signal if the brakes are 25 applied by the train stop ATS. If desirable, of course, other auxiliary train stops could be provided to correspond to intermediate speeds, but in practice one auxiliary 30 train stop will usually be all that is desirable. The speed of the train is estimated by means of a time element device comprising a neutral relay R and a time control device TC which is represented dia- 35 grammatically and is illustrated in greater detail in Figures 2-6. This time element device serves to determine whether the time taken for the train to pass over a measured track which extends from the 40 insulator 101 to the auxiliary train stop ATS is less or greater than a predetermined amount. Immediately below the insulator 101 is shown an insulator 102; this is provided to effectively insulate the 45 rails at the points from the main track, as these rails are usually guarded by a short local track circuit.

On the right hand side of the insulator 101 on the upper rail, a short insulated rail 110 is fitted in the main track. This insulated rail is electromagnetically connected to a battery B and to the armature 112 of the relay R. The rail 111 which extends from the insulator 101 to the left of the 55 rail 110 beyond the auxiliary train stop ATS to the insulator 113 is also insulated and is electromagnetically connected to the working contact 114 of the armature 112. BW represents the block wire which 60 extends from one signal cabin to the next in series with a polarized relay PR. This relay can only operate when the direction of current in the block wire corresponds to the signal "Train on line" having been set 65 up. Under these circumstances armature

116 is attracted and a circuit extends from rail 117 through armature 116 and its working contact, relay R, battery B to insulated rail 110. This circuit obviously cannot be completed until a train connects 70 the rail 110 with the lower rail 117.

It will be assumed that the signals are at "danger" and the train has advanced beyond the distant signal. Under these circumstances the engine-driver should have 75 reduced the speed of the train according to instructions. But whether or not, as soon as the front wheels of the train pass beyond the insulators 101 the rails 110 and 117 are electrically connected together and the relay R energizes in the previously traced 80 circuit. The relay then attracts its armatures 112, 118 and 119. At armature 112 it completes a locking circuit for itself independent of the rail 110 which may be 85 traced as follows:—Rail 117 armature 116, and its working contact, relay R, battery B, armature 112, contact 114, to rail 111 which is now connected by the train to the rail 117. The relay R therefore remains 90 energized until the last carriage of the train passes beyond the insulator 113. At its armature 119, a circuit is closed for the electromagnet 120 of the time control device TC as follows: positive pole of bat- 95 tery B', electromagnet 120, armature 119 and its working contact to negative pole of battery B'. The electromagnet 120 energizes and attracts its armature 121. This armature is provided with two arms 122 100 and 123, the arm 122 corresponding to the projection 126 (see Figure 2) while the arm 123 is substantially identical to that described with reference to Figures 2-6. The arm 122 releases the balance weight 129 105 which commences to oscillate under the control of the electromagnet 146. By means of its cam 150 the balance weight 129 causes the roller 151 by means of the pawl 170 to advance the ratchet wheel 133 step by step 110 and to rotate with it the cylindrical disc 134. The arm 123 moves sufficiently to force the roller 136 into engagement with both the surface 125 of the arm 123 and the surface of the cylindrical disc 134, the 115 roller advances and after a predetermined time comes opposite the recess 152 when the armature 121 is no longer prevented from moving to its fully attracted position to engage with the contacts 144 and 145, when 120 a circuit is closed as follows: Positive pole of battery B², contact 144, armature 121, contact 145, contact 155, controlled by auxiliary train stop ATS by being mechanically coupled thereto, winding 157 of the 125 electromagnet controlling said train stop, armature 118 to negative pole of battery B' which is connected in series with battery B². The train stop magnet is thereby 130 excited and its arm moved to the "off" po-

sition. Now if the train had been exceeding a predetermined speed it would have reached the auxiliary train stop before this operation could have taken place as the time for the roller 136 to come opposite the depression 152 has been set to take a predetermined time according to the estimated speed which the train must not exceed; consequently the train on reaching train stop ATS would have its brakes applied. If, however, it has been travelling below the predetermined speed, then it will not be affected and will only have its brakes applied if it passes the train stop TS. Normally the train should be pulled up at the home signal but if it should pass the train stop TS, its brakes will be automatically applied, however, its speed will not be high enough to allow it to travel beyond the block clearance under these conditions.

On the assumption that everything is clear, then all the signals governing the motion of the train (in addition to the home signal, the starting signal X and the advance starting signal Y are also shown) will be at the "clear" position. Contacts 160, 161, and 162 which represent contacts controlled in the well known manner from the signal levers and in accordance with their position are opened when the signals are at danger and are closed when the signal is at "clear"; consequently when all the signals are at the "clear" position, a circuit for the electromagnet 120 may be traced as follows: positive pole of battery B', electromagnet 120, lower rail 117, contacts 160, 161 and 162 in the operated position, to negative pole of battery B'; it will therefore be seen that electromagnet 120 is energized as soon as the signals are lowered, so that before the train reaches the rail 110 the roller 133 will have approached if not actually reached the depression 152; consequently the armature 121 will make contact with contacts 144 and 145 in considerable advance of the train. The circuit of the auxiliary train stop ATS however is not completed until relay R is energized as this is open at armature 118 and as this relay can only be energized by a train connecting rail 110 with rail 117 it follows that the auxiliary train stop will only be in an off normal position during the passage of a train over the rail 111. The auxiliary train stop ATS is provided as usual with a contact operating device corresponding to its "off" and "on" positions, the armature 155 being adapted when the train stop is in the off position to be withdrawn from connection with its resting contact so as to bring into circuit a resistance 163 whereby the current consumption is reduced, it being understood of course that a considerably heavier current is required

for energizing the train stop 157 than for maintaining it in its off position. Armature 164 is provided for detection purposes, positive or negative battery being connected by armature 164 from the rail 117 to an auxiliary conductor 165 extending to a detector DE in the signal cabin, so that the position of the train stop may be observed.

It will thus be appreciated that by means of the present invention, a time element device has been produced which always starts under the same condition, which requires very little energizing current, just sufficient to cause the roller to engage between the disc and the auxiliary arm of the armature, while the timing is highly accurate and the exact amount can be adjusted by varying the starting position of the roller. A single dry cell is sufficient for maintaining the oscillator and under ordinary circumstances should last for several years.

It should be mentioned that the time element device with the neutral relay may be applied to any part of the line where a permanent speed reduction is required as on curves or the turnout of a junction or at terminal stations to ensure that a train does not enter at too high a speed.

What we claim and desire to protect by Letters Patent is:

1. A time element device comprising an electromagnet, an armature controlled by said electromagnet, contact members adapted to be operated by said armature to prepare a holding circuit for said electromagnet, a member set in movement against a continuously acting restoring force when said electromagnet is excited and a controlling device by which the completion of the movement of said member is only enabled to take place after the lapse of a predetermined time.

2. A time element device comprising a member adapted to be operated against a continuously acting restoring force, means for locking said member in its operated position, a second member adapted to be set in movement by said first member, also against a continuously acting restoring force and controlling means by which the completion of the movement of said second member is only enabled to take place after the lapse of a predetermined time.

3. A time element device comprising a member adapted to be operated against a continuously acting restoring force, an electromagnet for locking said member in its operated position, a second member adapted to be set in movement by said first member, also against a continuously acting restoring force and controlling means by which the completion of the movement of said second member is only enabled to take place after the lapse of a predetermined time.

4. A time element device comprising a member adapted to be operated against a continuously acting restoring force, means for locking said member in its operated position, contacts adapted to be closed when said member is in its operated position, an electromagnet in circuit with said contacts and adapted to be energized when said contacts are closed, an armature on said electromagnet and controlling means by which the completion of the movement of said armature is only enabled to take place after the lapse of a predetermined time. 70
5. A time element device comprising an electromagnet, an armature controlled by said electromagnet, contact members adapted to be operated by said armature to prepare a holding circuit for said electromagnet, a second electromagnet, contact members adapted to be closed by the armature of the first electromagnet to complete an energizing circuit for said second electromagnet, an armature controlled by said second electromagnet and a controlling device 75 by which the completion of the movement of said second armature is only enabled to take place after the lapse of a predetermined time. 80
6. A time element device comprising a quick-moving member adapted to be operated against a continuously acting restoring force, a second member adapted to be set in movement by said first member also against a continuously acting restoring force, controlling means by which the completion of the movement of said second member is only enabled to take place after the lapse of a predetermined time, and means for removing the operating force on said quick-moving member to permit it to restore at once to its normal position under the sole control of the continuously acting restoring force. 85
7. A time element device comprising a member adapted to be raised against its own weight, a second member adapted to be set in movement when said first member is raised, also against its own weight, and controlling means by which the completion of the movement of said second member is only enabled to take place after the lapse of a predetermined time. 90
8. A time element device comprising an electromagnet, an armature adapted to be raised against its own weight when said electromagnet is energized, contact members adapted to be operated by said armature to complete a holding circuit for said electromagnet, a second electromagnet, contact members controlled by the armature of said first electromagnet to complete the energizing circuit for said second electromagnet, an armature adapted to be raised against its own weight when said second electromagnet is excited and controlling means by 95
- which the completion of the upward movement of said second armature is only enabled to take place after the lapse of a predetermined time. 100
9. A time element device comprising a member adapted to be operated against a continuously acting restoring force, means for locking said member in its operated position, a second member adapted to be set in movement by said first member also against a continuously acting restoring force, controlling means by which the completion of the movement of said second member is only enabled to take place after the lapse of a predetermined time and means for controlling said locking means to permit said first member to resume its normal position under the control of the continuously acting restoring force. 105
10. A time element device comprising a relay, an electromagnet adapted to be energized when said relay is excited, an armature on said electromagnet adapted to be subjected to a tractive force when said electromagnet is energized, an obstructing member for preventing the completion of the movement of said armature and means for rendering said obstructing member ineffective after a predetermined time. 110
11. A time controlled element comprising a member adapted to be operated against a continuously acting restoring force, an obstructing member adapted to prevent the completion of the movement of said first member and means for rendering said obstructing member non-effective to prevent the completion of the movement of said first member after a predetermined time. 115
12. A time controlled element comprising a member adapted to be operated against a continuously acting restoring force, a movable member, an obstructing member adapted to prevent the completion of the movement of said first member and means for coupling said obstructing member with said movable member so as to enable it to be withdrawn from the path of said first member after a predetermined time. 120
13. A time controlled element comprising a member adapted to be operated against a continuously acting restoring force, a member having a smooth surface adapted to be rotated at a regular rate, a roller adapted to be interposed between said first member and the surface of said rotatable member, said first member being arranged to force said roller against said surface when first operated, means for causing said rotatable member to move thereby causing said roller to roll between said members to permit the complete movement of said first member when the roller has advanced a predetermined distance. 125
14. A time controlled element comprising a member having a curved surface, a second 130

- member having a cylindrical surface and adapted to rotate about its axis, which axis approximates to the centre of curvature of the curved surface of said first member, a roller interposed between the surfaces of said members, means for causing said first member to cause said roller to engage with said surfaces and means for causing said second member to rotate.

10. A time controlled element comprising an electromagnet, an armature mounted on a pivot and adapted to be attracted by said electromagnet against a continuously acting restoring force, a member having a concave surface secured to said armature, a member having a cylindrical surface and adapted to rotate about its axis which axis approximates to the centre of curvature of the concave surface of said first member, a roller interposed between the surfaces of said members, means for energizing said electromagnet to attract said armature and cause said curved member to press said roller against the cylindrical surface of said rotatable member and means for causing said cylindrical member to rotate.

15. A time controlled element comprising an electromagnet, an armature for said electromagnet, an obstructing member adapted to prevent said armature completing its movement, a member having periodic movement and means controlled by said periodically moving member for effecting the removal of said obstructing member and permitting the full movement of said armature after a predetermined time.

20. A time controlled element comprising an operating member, an obstructing member for preventing the complete movement of said operating member and a member having a regular periodic movement for effecting the removal of said obstructing member and permitting the full movement of said operating member after a predetermined time.

25. A time controlled element comprising an operating member, an obstructing member for preventing the complete movement of said operating member, a member having regular periodic movement, and means controlled by said operating member after a partial movement for initiating the operation of the member with a periodic movement and means controlled by said periodically moving member for removing said obstructing member from the path of said operating member after a predetermined time to permit said operating member to complete its movement.

30. A time controlled element comprising a member controlled so as to have a periodic movement, means for normally locking said member in an extreme position, means for operating said locking means to initiate the movement of said member, an electromagnet, a magnetic member secured to said periodically moving member and adapted to swing within the magnetic field of said electromagnet, and contact members controlled by said periodically moving member adapted to complete a circuit for said electromagnet when said magnetic member is approaching said electromagnet, to cause said periodically moving member to be maintained in regular movement.

35. A time controlling element comprising an electromagnet, an armature adapted to be attracted when said electromagnet is energized, a projecting member on said armature, a member adapted to be controlled so as to have a regular periodic movement and adapted to be normally held by said projecting member in an extreme position and to be released when said electromagnet is energized, and means for maintaining said member in regular periodic movement, whereby said member may be again secured in an extreme position when said electromagnet is de-energized.

40. A time controlling element comprising a pivoted member adapted to oscillate about a central position, a cam secured to said oscillating member having a gradually graded surface on one side and a steeply graded surface on the other side, and a projecting member adapted to engage with said steeply graded surface to hold the oscillating member in an extreme position and adapted, after being operated to release the oscillating member to again engage said steeply graded surface, the projecting member being permitted to slide easily over said gradually graded surface without interfering with the movement of said oscillating member to enable it to be again locked in an extreme position.

45. A time controlling element comprising an electromagnet, an armature controlled by said electromagnet, a projecting member on said armature, an oscillating member adapted to be normally held by said projecting member in an extreme position and adapted to be released when said armature is attracted, a magnetic member mounted on said oscillating member, a second electromagnet adapted, when excited, to exert a controlling action on said magnetic member, contacts controlled by said oscillating member adapted to be closed to complete a circuit for said second electromagnet when said magnetic member is ap-

- proaching the poles of said electromagnet, whereby said oscillating member is maintained in regular movement, and a cam mounted on the shaft of said oscillating member and having a steeply graded surface for engaging with said projecting member and a gradually graded surface to permit said oscillating member advancing to an extreme position where it is held by the projecting member after the armature has been released due to the de-energization of said first electromagnet.
24. A time controlled element comprising an electromagnet, an armature controlled by said electromagnet having a member with a concave surface on one side and a projecting member on the other side, an oscillating member normally held in an extreme position by said projecting member and adapted to be released when said electromagnet is energized, a pawl, a ratchet wheel, a cam on the shaft of said oscillating member adapted to engage said pawl and cause the ratchet wheel to be advanced one step for each oscillation or part oscillation of said oscillating member, a cylindrical disc caused to rotate with said ratchet wheel and having its axis approximately coinciding with the centre of curvature of the concave surface of the member secured to the armature, a roller loosely supported between the surface of said cylindrical disc and said concave surface and adapted to engage with said surfaces when said armature is attracted to prevent the full movement of the armature, there being a recess in said curved surface in which said roller is adapted to enter when the cylindrical disc has rotated a predetermined amount to permit full movement of said armature, and means for permitting said projecting member to again engage and hold said oscillating member in an extreme position when the electromagnet is de-energized.
25. A time controlled element comprising an electromagnet, an armature for said electromagnet, a member having regular periodic movement adapted to control the movement of said armature when attracted, and contact members adapted to be operated by said armature on completion of its movement to close an electrical circuit.
26. A time controlled element comprising an operating member, a periodically moving member adapted to be set in movement by said operating member, a second member adapted to be advanced against a continuously acting restoring force by said periodically moving member a predetermined distance in a predetermined time.
27. A time controlled element comprising an electromagnet, an armature for said electromagnet, a member having regular periodic movement adapted to be released when said armature is attracted, a second member adapted to be advanced by said periodically moving member to a predetermined position in a predetermined time, and means for adjusting the initial position of said second member so that the time taken to reach the predetermined position may be varied.
